UNITED STATES PATENT OFFICE.

ANDREW FORBES, OF PHILADELPHIA, PENNSYLVANIA.

BOTTLE-WRAPPING MACHINE.

No. 797,846.

Specification of Letters Patent.

Patented Aug. 22, 1905.

Application filed August 1, 1904. Serial No. 219,054.

To all whom it may concern:

Be it known that I, ANDREW FORBES, a citizen of the United States, residing at Philadelphia, in the county of Philadelphia and State of Pennsylvania, have invented certain new and useful Improvements in Bottle-Wrapping Machines, of which the following is a full, clear, and exact specification.

This invention relates to machines for labeling and wrapping packages, and is particularly designed to label and wrap bottles of either cylindrical or flattened form and will be described as a bottle-wrapping machine in the ensuing specification.

My invention is embodied in a machine constructed to operate on a roll or web of paper to first print one or more labels thereon in a given length (subsequently to become a blank) in one or more colors, to next dry the ink, then to sever the web into blanks each bearing one or more printed labels, next to surround one of said labels with a weakened or perforated break-line and paste said label on its under side in order that it will adhere to a bottle, also at this stage pasting the end of the blank by the same pasting mechanism. Such a wrapper is described in my United States Patent No. 759,602, dated May 10, 1904. In the further traverse of the blanks through the machine a bottle is deposited on the gummed surface of the gummed label of a wrapper-blank and a supplemental wrapper of protective paper or board preferably embossed to remain permanently corrugated is deposited on the wrapper-blank adjacent to the bottle, the corrugated supplemental wrapper serving as a cushion. The longitudinal edges of the wrapper-blank are then folded over the bottle and supplemental wrapper and the bottle grasped and rotated to wrap the two wrappers or blanks around it, the mechanism being so timed that in labeling and wrapping flat or oval bottles the gummed label will be applied to a flat side of the bottle and the other or wrapper label will also be exposed at a flat side of the complete package. The final turn of the bottle causes the gummed end of the label to adhere to the body of the wrapper-blank, which is of course wrapped about the bottle, thus providing a printed label pasted to the bottle and remaining thereon and designed to be severed from the wrapper when the latter is removed, owing to the weakened or perforated break-line surrounding said label, (which I will herein-

after designate as the "package-label" and the other label on the same blank as the "wrapper-label.")

Referring to the accompanying drawings, in which similar letters and numerals of reference are used to indicate corresponding parts in each of the several views, Figure 1 is a side elevation of the machine complete ready for operation. Fig. 1^a is a detail view of the actuating draw-roll. Fig. 2 is a plan view of the complete machine. Fig. 3 is a plan view of the printing mechanism. Fig. 4 is an end view of the printing mechanism, and Fig. 5 is a side elevation thereof. Fig. 6 is a detached view of the inking apparatus; Fig. 7, a plan view of the same. Fig. 8 is a view of the printing mechanism, showing the inking - roller in position after having inked the printing-faces; and Fig. 9 is a sectional view on the line 9 9 of Fig. 8. Fig. 10 is a side elevation of the mechanism for cutting, perforating, pasting, and wrapping. Fig. 11 is a plan view of the same. Fig. 12 is an end view thereof looking in the direction of the arrow, Fig. 10. Fig. 13 is a similar view looking in the opposite direction. Fig. 14 is a horizontal sectional view on the line 14 14 of Fig. 10. Fig. 15 is a detail view of the mechanism for operating the bottle - wrapping fingers. Fig. 16 is a sectional view on the line 16 16 of Fig. 15, and Fig. 17 is a plan view of the same. Fig. 18 is a detached plan view with the bottle in position to be turned. Fig. 19 is a sectional view taken on the line 19 19 of Fig. 18. Fig. 20 is a section on the line 20 20 of Fig. 19. Fig. 21 is a detail sectional view on the line 21 21 of Fig. 18. Fig. 22 is a side elevation of the protective-paper and bottle feeding mechanism. Fig. 23 is a detached sectional view of the protective-paper hopper and device for feeding the same to proper position. Figs. 24, 25, and 26 are detail sectional views thereof. Fig. 27 is a detached sectional view of the wrapper cutting, perforating, and gumming rollers; and Fig. 28 is a plan view thereof. Figs. 29, 30, 31, 32, and 33 show the several steps in the operation of the machine.

Briefly stated, the machine as a whole is mounted in a frame comprising legs A, sides B and C, and guide or supporting tables D and D'.

Secured to the table D are standards d, having at their upper ends bearings for a shaft or spindle 1, carrying a roll or web of paper

G, the free end of which is carried beneath a guide-roll H to maintain the web of paper in contact with the upper surface of the table D. Suitably journaled at the opposite end of the table D are draw-rolls I and J, actuated from the main shaft of the machine.

During its passage from the guide-roll H to the draw-rolls I and J two labels are printed upon the web of paper, one to remain permanently thereon and the other to be in a subsequent operation of the machine provided with a weakened break-line and pasted to the article to be wrapped, herein shown as a flat bottle or flask.

My invention contemplates the printing of labels in two or more colors, (my present machine being fitted to print in three colors, involving six plungers, chases, &c.;) but as the printing mechanism for each color will be merely a duplicate of the mechanisms shown, the ink-fonts being supplied with ink of any desired color, I have shown but two printing devices—one to print the package-label and the other to print the permanent or wrapper label, we will say, in black. Duplicates of these printing devices for additional colors are in practice located between the guide-roll H and the draw-rolls I and J, but are omitted from the drawings by the breaking away of the frame and connecting parts.

Secured to the table D, between the guide-roll H and draw-rolls I and J, are columns K in pairs, each provided at the upper end with bearings within which is journaled a crank-shaft L, united by connecting-rod L, with a plunger 5 reciprocating vertically in guide-grooves 4 in the inner faces of the columns K. The under surfaces of the plungers 5 are each fitted to receive a "chase" M, carrying the type set for the matter desired to be displayed on the labels. The columns K are adjustable longitudinally or lengthwise of the table, so as to be spaced for printing labels on wrappers of different sizes for larger or smaller bottles.

Horizontal guide grooves or ways 6 are formed on opposite sides of the plungers 5, (see Figs. 8 and 9,) for a purpose to be presently explained.

Inking mechanism for the type is located at the side of the table D abreast each plunger 5 and comprises an ink well or tank 7, rigidly secured to one of the columns K of each pair, an ink distributing or supply roll 8 being journaled at the outer or discharge end thereof and supplying ink to a train of rolls 9 and 10, the latter distributing ink on the traveling inking-roll 11 for the form locked in the chase. The rolls 8, 9, and 10 are intermittent in their rotation, being carried on shafts journaled in a rocking frame 12, pivoted at its upper corner to the ink-well 7 on a stud 13, as shown in Figs. 4 and 6, and actuated from the plunger 5 through connecting-rod 14, pivoted at one end to a stud pro-

jecting from the plunger and at the other end to a geared segment 15, pivoted on a bracket 16, secured to the column K, its toothed segmental end meshing with a pinion 17, mounted on the end of the shaft of the ink-supply roll 8. The shafts of the rolls 10 are extended at their ends and carry friction-wheels 18, arranged in frictional or driving contact with friction-wheels 19, mounted on a shaft 19^a, also journaled in the rocking frame 12, one of said friction-wheels being located for driving contact when the rocking frame 12 is in the position shown in Figs. 3, 4, and 6, with a friction-wheel 20, keyed to a counter-shaft 20^a, journaled in bearings at one side of the main frame. This shaft 20^a is connected by gears 21 22 to the main shaft 23 of the machine and actuated thereby.

The traveling inking-roll 11 is mounted on a shaft 24, secured at its ends between two L-shaped bars 25, the long legs 26 of which are provided with slots 27, engaging studs 28, projecting from the columns K, the short legs 28' of said angle-bars being provided at their upper ends with inwardly-extending studs 29, which during certain portions of the movement of the plunger 5 enter and traverse the horizontal ways 5 at the base thereof. (See Figs. 8 and 9.)

An elbow-lever 30 is pivoted on a stud 31, projecting from the column K, Figs. 4 and 8, its lower end being connected by a connecting-rod 32 to the shaft 24 of the L-shaped slide-bars 25, and to the short arm of said lever is pivoted the lower end of a rod 33, the upper end of which terminates in a T-shaped head 34, the ends of which travel in sister cam-grooves 35, formed in the adjacent faces of two disks 36 36, keyed to the projecting end of the crank-shaft L. Beneath the inking-roll frame 12 a stout spring 37 is secured to the base of the column, its free end rising in contact with the shaft 19^a, the stress of said spring being exerted to move the frame 12 on its pivot 13 away from the column.

As thus constructed it will be seen that the rotation of the crank-shaft (assuming that the parts are positioned as in Fig. 4) will move the plunger upward, and the link 14, pivoted thereto, will cause the movement round its pivot of the toothed segment 15, this in turn rotating the ink-supply roll 8, which will distribute ink to the rolls 9 and 10, and the latter will ink the traversing inking-roll 11.

As the plunger rises the elbow-lever 30 will at the proper time be moved by the cam-wheels 36, thus causing the pins 29 of the L-shaped bar 25 to enter the ways 6 of the plunger, and the further movement of the parts will cause the inking-roll to travel across the form of type locked in the chase, thus inking the type by a forward and back pass of the traveling inking-roll. As the bar 25 moves toward the plunger the rocking frame will be relieved from pressure at that side and the

spring 37 will exert its force to move the lower end of said frame toward the plunger, thus severing driving connection between the friction-wheels 19 and 20.

As the printed web leaves the printing mechanism, being drawn off by draw-rolls I and J at the end of the table D, the web passes beneath the roll J and back under the table above a steam-table 40 or other suitable apparatus to dry the freshly-printed labels. The top draw-roll I is cut away or chambered at the center, as shown in Fig. 3, in order that it will not contact with the fresh ink and smear or blur the same as the web of paper carrying the labels passes between the rolls. The steam-table 40 is fitted with guide or supporting rolls 41 to sustain the web of paper in its passage above the same, these rolls also being reduced in diameter at the center to avoid contact with the freshly-printed labels.

From the drying-table the web of paper passes to the table D', upon which is supported a knife to sever the web into blanks of suitable lengths, a device for perforating one of the labels of each blank about its margins, and a device to gum the back of the label so perforated and also gum the rear end of each blank. The table also supports a hopper to contain bottles which are to be deposited upon the wrappers and wrapped therein and also a hopper to contain a number of protective or supplemental wrappers, one to be deposited upon the wrapper proper as each bottle is deposited thereon.

As the printed web passes over the surface of the table D' it will pass beneath the cutting device, herein shown as a roll 42, armed with a knife or blade 43, shaped to cut the web without waste to leave a narrow tongue upon the end last passing the knife.

The web of paper being severed at this point is passed along the table beneath a plunger 44, provided with a device 45 to surround the leading label with a weakened line favoring its ready severance from the wrapper-blank, the device herein shown consisting of punches or pins 45 to perforate the wrapper, and thus establish the weakened line by a row of perforations. This leading label of the blank I have hereinbefore termed the "package-label," as it is designed to be permanently attached to the bottle in the subsequent step of wrapping. This plunger consists of a platen armed with the pins 45 and connected at its ends with uprights 44^a, fitted to slide vertically in the standards 44^b and connected by strap 44^c, having lugs 44^d, with the plunger proper by pin 44^e. The strap 44^c encircles a cam on shaft 44^f, actuated by gear 73, mounted and actuated as hereinafter described.

As the web passes along over the table D' it next passes beneath a pasting device, herein shown as a shaft 46, carrying a segmental roll the surface of which is broken by a deep V-shaped notch 47, thus providing a surface 48

to apply a line of paste to the rear end of each label and a pasting-surface 49 of a size and shape corresponding to the bottle-label within the perforated outline. It will be understood, of course, that the V-shaped notch will be of a width to accurately space the pasting-surface apart to deposit paste upon the rear end margin of one blank and the package-label of the next succeeding blank.

On either side of the segmental roll or pasting-surfaces 48 and 49 feed-rolls 49^a, Figs. 27 28, are mounted on the shaft 46 to feed the wrapper-blanks along.

In practice I prefer to support the thrust of the cutting and pasting rolls and assist the feed of the blank through the machine by journaling beneath said rolls counter-rolls 42' 46' to take the thrust and rotate as the paper passes above it.

It will be understood, of course, that the feed of the web of paper through the machine is intermittent and that provision is made for momentarily stopping said feed during the steps of printing and perforating the blanks.

The cutting, perforating, and pasting mechanism is driven from the main shaft 23 of the machine through a counter-shaft 50, bearing at its end a bevel-gear 51, meshing with a similar gear 52, keyed to a shaft 52', Figs. 10 and 14, running transversely of this portion of the machine beneath the table D'. From this shaft motion is transmitted by a train of gearing 53 54 55 to a shaft 56, carrying a bevel-gear 57, which meshes with a larger bevel-gear 58, carried at one end of a shaft 59, supported in bearings parallel to the side of the table D'. Upon this shaft 59 are keyed three bevel-gears 60 61 62, meshing with similar gears 63 64 65, respectively, on the lower ends of vertical spindles 66 67 68, the upper ends of which are provided with bevel-gears 69, 70, and 71, meshing with bevel-gears 72 73 74, secured, respectively, to the gumming, perforating, and cutting mechanism, to which motion is thus imparted from the main shaft of the machine and in unison with the printing mechanism.

A label-blank having now been printed, severed from the web, one label perforated, and the blank appropriately pasted, the blank is fed forward beneath a vertically-movable bottle-hopper 75, consisting of a vertical trough open at top and bottom and at one end, supported from the table D' by a bracket 76, having guide-grooves 77 and 78, Fig. 11, the latter forming a guideway for the hopper. The guide 78 is provided with a vertical slot in which a supporting-stem 78^a has movement. This stem is at its end connected to one end of a lever 80, pivoted to the end of a bent arm 81, projecting from the bracket and terminating flush with the side of the frame, the other end of said lever being pivoted to a connecting-rod 82, provided at its lower end with a

stud armed with a friction-roll adapted to travel in a cam-groove 83, formed in the face of the gear-wheel 84, which meshes with a gear-wheel 129 on the transverse shaft 52' and is driven thereby. In order to maintain the connecting-rod 82 in the vertical operative position, I pivot to its lower end one end of a steady-link 86, the other end of which is pivoted on a stud projecting from the side frame of the machine.

The bottles are supported within the receptacle 75 by means of retaining-fingers 87, pivoted on either side of the hopper-guide 78 on rods extended to the rear and secured in the upright part of the bracket 76 and maintained normally in the position shown in Figs. 10 and 22 by stout coiled springs 87^a, encircling the rods and secured at one end to the fingers and at the other end to a fixed point in a manner well understood. The outer ends of these supporting-fingers are coupled to slide-rods 88, pivoted at their upper ends on pins or rods 89, the rear ends of which are extended back and fitted with T-shaped heads 90 or guide-blocks, which travel vertically in the T-shaped guide-grooves 77 of the bracket, heretofore referred to. At a suitable point within the T-shaped guide-grooves 77 are secured stops 91 for a purpose to be explained.

In operation the vertically-movable hopper and retaining-fingers will at the appropriate time be moved downward by the operation of cam-grooves 83, connecting-link 82, and lever 81 to deposit a bottle upon the gummed or package label of the wrapper. At the point where a bottle is about to be deposited upon the wrapper the guide-blocks 89 come in contact with stops 91, thus arresting the movement of the links 88 while the hopper continues its descent, the result being that the points of the retaining-fingers are removed from beneath the lower bottle just as it is brought in contact with the label. As the hopper again rises, owing to the action of the springs 87^a, the retaining-fingers will resume their retaining horizontal position as the hopper is raised by its operating mechanism.

A bottle having been deposited upon the gummed or bottle label of the wrapper, a protecting supplementary wrapper 92 is next fed onto the wrapper-blank adjacent to the bottle from a hopper 93, having a downwardly-inclined bottom 94, (shown best in detail in Fig. 23,) such protecting-wrapper consisting in the instance shown of corrugated blanks of paper or board. As the superposed blanks will be nested within the hopper, the corrugations of the several blanks will intermesh, which necessitates a mechanical positive feed for each blank to push it from the lower end of the hopper. I have shown such a mechanism in Figs. 22 to 26, the hopper-bottom 94 being provided with a slotted guideway 95, within which is mounted to travel a cross-pin 96, on which is pivoted a head 97, traveling in the

guideway 95 and having an upwardly-projecting finger 98, projecting a distance through the slotted bottom of the hopper practically equal to the thickness of the corrugated blank. This head 97 is connected by a connecting-rod 99 with the upper end of a bent lever 100, the vertical arm of which is fulcrumed in a bracket 101, secured to the side of the machine-frame, the lower end of said lever having pivoted thereto one end of a link 102, the other end of which is pivoted on a wrist-pin 103, projecting from the face of a gear-wheel 104.

Gear 104, deriving motion from gear 84, will cause the operation of the lever 100 back and forth a distance sufficient to cause the finger 98 to push a corrugated blank from the hopper 93, the upper rear end of the finger being rounded to avoid abrading the under surfaces of the protective paper and the stroke or movement terminating just short of the discharge-opening of the hopper, so that there will be no danger of the finger catching the edge of the lowermost blank in its return movement.

After the supplemental or protecting cushioning-wrapper 92 has been deposited upon the wrapper adjacent to the bottle the next operation of the machine is to fold the longitudinal edges of the wrapper over the bottle and throughout the length of the wrapper. Mechanism for this operation is illustrated in Figs. 10, 12, 18, and 21 and comprises folding-fingers 105 106 107 107, Fig. 18, projecting up through slots 108 in the table D' and secured beneath the table to rock-shafts 109, journaled parallel with the edges of the table. The folding-fingers are of different heights, since those lettered 105 are designed to fold the wrapper over the bottle and must project some distance above the table, while the fingers 106 are of less height to fold the rising web of the margin of the wrapper, and the fingers 107 107 fold the edges of the wrapper flat upon the cushion-wrapper 92 and upon the body of the wrapper at its extreme end, as shown in Fig. 18. Each rock-shaft is provided with a crank-arm 110, the end of which is connected by link 111 with a lever 112, pivoted to the end of the machine-frame, the other end of the lever 112 being connected by link 113 with the cross-head 114 of a vertical slide 115, guided in its vertical movement by a suitable bracket 116, attached to the machine-frame. This slide 115 is connected by a connecting-rod 117 to a crank-arm 118, carried on the end of a rotary shaft 119, mounted in suitable bearings at about the longitudinal center of the machine-frame. The inner end of this shaft 119 is provided with a pinion 120, (see Figs. 12 and 14,) which meshes with a toothed segment 121, pivoted on a bracket 122, secured to the side of the machine-frame, said pivoted segment being connected by a link 123 to one end of a rock-lever 124, fulcrumed in a bear-

ing 125, carried by a bracket 126, projecting from the machine-frame. The outer end of the lever 124 is of L shape, the short arm thereof rising from the fulcrum and the long arm extending horizontally and being provided at its end with a friction-roll 127, which travels in a cam-groove formed in one face of a gear-wheel 128, which is driven from a gear-wheel 129, keyed to the outer end of the transverse shaft 52'. (See Figs. 10, 12, and 14.)

From this construction it will be seen that the folding-fingers are operated from the main shaft 23 of the machine through the connections already described through the shaft 53, thence through the rocking lever 124, segmental gear and pinion 120 and 121, rock-shaft 119, crank-arm 118, connecting-rod 117, slide 115, links 113, levers 112, and the rock-shafts, to which the folding-fingers are secured.

The longitudinal edges of the wrapper having now been folded over upon the bottle and upon itself, means are provided to grasp and rotate the bottle and wrapper to envelop the bottle within the wrapper and paste the gummed edge of the wrapper, which will now be described.

The bottle-grasping devices consist of spring-pressed clasps or fingers 130, pivoted at the inner ends of stub-shafts 131, which are mounted to rotate in bearings 132, but are fixed against endwise movement therein by means of screws 133 passing through the walls of the bearings and entering a circular groove in the shaft. To the outer ends of the shafts bevel gear-wheels 134 are secured by a spline in such manner that the gear-wheels may move longitudinally on the shafts, but the shafts must rotate with them. These gear-wheels mesh with gear-wheels 135, each keyed to the upper section of a telescopic shaft to be presently described. The two gear-wheels are held in mesh by a bearing-bracket 136, embracing both shafts, as best shown in Fig. 19. The bearing-blocks 132 are mounted upon a frame or table 137 to have limited lateral motion with respect to said table—that is to say, in the direction of the length of the shafts 131—to that end being seated in guideways 138 in the top of said table, and they may also rest and slide upon horizontal ledges 139 of the table. The inner edges of said ledges are provided with guide-grooves 140 to receive and guide projecting fins or ribs 141, formed on or secured to a slide-frame 142, also resting on the ledges 139. These slide-frames are provided at their lower sides with racks 143, engaging pinions 144, carried by a transverse shaft mounted in suitable bearings on the table 137, said pinions also meshing with a geared segment 145, pivoted on a stub-shaft secured to a vertical part of said table 137, the segment being connected by a connecting-rod 146 to the upper end of a lever 147, pivoted at its lower end on a cross-shaft 148,

mounted in bearings carried by the machine-frame. To the lever 147, between its ends, is pivoted one end of a connecting-rod 149, the other end of which carries a friction-roll, which is seated in a cam-groove 150 in the face of a gear-wheel 151, mounted upon a transverse shaft 152, extending from side to side of the machine.

From this construction it will be seen that the table 137 and its adjuncts—that is to say, the bottle-clasps and their coacting mechanism—will be moved at intervals from the position shown in Fig. 10—that is, a position clear from the hopper and the bottles—to a position beneath said hopper, where the clasps will grasp the wrapper and bottle that has been deposited thereon.

Upon the shaft 152 is also mounted another wheel 153, having a cam-groove 154, within which travels a friction-roll 155, carried by the end of a connecting-rod 156, the other end of which is pivoted to a lever 157, which is also mounted on the cross-shaft 148. The upper end of this lever is connected by a link 158 with the lower end of a Y-shaped lever 159, fulcrumed at 160 in a suitable bracket attached to the machine-frame, the upper or Y part of the lever being provided with laterally-projecting pins 161 to engage opposite sides of the depending end of a slide-bar 162, the horizontal portion of which is guided in a bracket 163, secured to the top of the frame or table 137. The inner end of this slide-rod is connected by links 164 to the ends of levers 165, pivoted at 166 to the table 137, the other ends of said lever 165 being pivoted at 167 to the bearing-blocks 132, so that movement imparted by the cam-groove through the connecting rod and lever will serve to move the bearing-blocks and their stub-shafts and the bottle-clasps toward and from each other to clasp or release a bottle, the shaft meanwhile sliding freely through the gear-wheels 134, but turning with them.

The bevel-gears 135, which actuate the gears mounted on the stub-shafts 131, carrying the bottle-clasps, are keyed to the upper end of shafts 168 of telescopic form, the lower part thereof being tubular, so that the upper end may slide longitudinally within it, but turn therewith. The lower tubular member of this shaft is provided with a bevel gear-wheel 169, meshing with a bevel gear-wheel 170, mounted on a transverse shaft supported in bearings in the machine-frame. Secured to the cam-disk 153 is a spring-actuated slide-bolt 174 of angular contour, (see Fig. 16,) the outer end of which is designed to engage notches 175, formed at intervals in the inner surface of a chain ring 172, thus locking the cam-disk and ring together, so that they will travel in unison when the bolt is so engaged with one or the other of the notches. As it is designed that this friction-ring should have an intermittent motion, however, I have made pro-

vision for disengaging the bolt from the notches of the ring as follows: Near the outer end of the bolt is arranged a small friction-wheel 176, which travels in contact with a cam-like rib or web 177, formed on the face of the bracket 173, the relations being such that as the wheel 153 rotates the bolt will at one point—namely, when the friction-wheel 176 arrives in contact with the cam-surface 177—be withdrawn from a notch, and the chain ring 172 remain at rest until the bolt has reached the next notch 175, within which it will enter and the movement of the ring be resumed. The purpose of this construction is that the bottle-turning mechanism shall only be caused to operate at that time when the bottle-clasps have been moved to grasp a bottle.

In wrapping flat or oval shaped bottles it is necessary that the bottle-clasps and the adjuncts carried by the frame or table 137 shall be given vertical movement to permit the bottle to be rolled. To accomplish this object, I provide below the frame 137 eccentric 178, carried by a shaft X, which is mounted in bearings carried by brackets secured to the machine-frame. The shaft also carries a chain-wheel 179, connected by a chain 180 with the chain ring 172, so that the shaft is revolved from said chain ring and the eccentric raise and lower the frame or table 137 at the time the bottle-clasps are in engagement with the bottle and wrapper and in rotation, it being understood, of course, that the purpose in making the shaft 168 telescopic is to accommodate the movements here described. In wrapping bottles of cylindrical form of course it will be understood that the vertical movement of the frame 137 and the bottle-clasps is unnecessary, and to suspend its action I preferably remove the eccentric 178 and substitute therefor cylindric rolls, or the frame may be clamped rigidly to the machine-frame when at its highest point, thus avoiding the effect of the eccentric, or the chain 180 may be slipped out of action.

From the foregoing construction it will be seen that movement of the bottle-wrapping mechanism is derived from the main shaft 23 through counter-shaft 50, shaft 52', gears 53 and 54, and a gear 54^a, Figs. 10 and 14, to the gear 151, carried by the shaft 152, on which is mounted the wheel 153, which has connection to intermittently rotate the toothed ring 172. This ring being connected by sprocket-chain 180 with the sprocket 179 transmits rotary motion through a gear 181 on the shaft of the sprocket-wheel and through a meshing gear 182 on the shaft which carries the bevel-wheels 170 to the bottle-clasps, the means actuating said clasps to grasp and release a bottle and to move said clasps beneath and from the bottle-hopper having been already described in detail.

It will be understood that the several steps

in the operation of the complete machine—that is, printing, cutting, perforating, gumming, feeding the bottle and supplemental wrapper, folding, and wrapping—are timed with respect to each other, so that the parts of the machine work as a harmonious whole, all actuated from the main driving-shaft, as before stated.

In operation the mechanism organized as described draws the paper from the roll G onto the table D beneath the printing mechanisms, where the labels are printed, in the instance shown two being printed within a space to form a wrapper-blank, as described. The two labels being simultaneously printed, the web of paper is now drawn beneath the table D and passing above the drying device 40 is fed onto table D', where it passes beneath and is operated on by the knife of the cutting-roll 42 to sever the web into wrapper-blanks, thence beneath the perforating-plunger 44, which perforates the margin of the package-label, and thence beneath the pasting device, which applies paste to the rear edge of each label and to the back of the package-label. The blanks still traveling toward the tail of the machine are brought successively to a position where the perforated and pasted package-label is beneath the bottle-hopper 75, at which time the hopper descends and deposits a bottle upon the pasted surface of the package-label, the bottle-hopper again ascending as a cushion-wrapper is fed onto the wrapper proper from the hopper 93 by means of the finger 98 and its actuating mechanism. The folding-fingers 105, 106, and 107 now come into action to fold the longitudinal edges of the blank over the bottle and cushion-wrapper, as shown in Fig. 18, and finally the wrapping devices move forward and the fingers 130 grasp the bottle and wrapper-blank and then rotate so that the wrapper is wound around the bottle, which may now be removed by an attendant or automatically by mechanism not shown in connection with this present application.

Having thus fully described my invention, what I claim as new, and desire to secure by Letters Patent of the United States, is

1. In a wrapping-machine, the combination with means for printing a label on a wrapper, of means for surrounding said label with a weakened break-line, means for gumming the under surface of said label, means for depositing thereon the article to be wrapped and inclosing said article within the wrapper.

2. In a package-wrapping machine, means for folding the longitudinal edges of a wrapper over the ends of a package and upon the body of the wrapper, movable-fingers means for operating said fingers to grasp the body of the wrapper, its folded edge and the package contained between them, and revolving them, whereby said package is completely inclosed within the wrapper.

3. In a package-wrapping machine means for feeding thereto a wrapper bearing a label of less diameter than the circumference of the package to be wrapped, means for gumming the unprinted surface of the label, means for depositing on said gummed surface of the label of the wrapper the package to be wrapped, and means for rotating the wrapper and package to inclose the latter within the former.

4. In a wrapping-machine, means for gumming the under rear edge of a wrapper bearing a label means for gumming the under surface of the wrapper beneath said label, means for depositing on such gummed surface the article to be wrapped and means for inclosing the article within the wrapper.

5. In a wrapping-machine, means for feeding thereto a wrapper bearing a label, means for surrounding said label with a weakened break-line, means for gumming the under surface of said label, means for depositing thereon the article to be wrapped and means for inclosing the article within said wrapper.

6. In a wrapping-machine means for inclosing a portion of the wrapper with a weakened break-line, means for gumming the under surface of said portion, means for depositing thereon the article to be wrapped, and means for inclosing said article within the wrapper.

7. In a package-wrapping machine, means for printing a wrapper-label and a package-label upon a wrapper, means for gumming the unprinted surface of the package-label, means for depositing a package on the gummed back of the package-label, and means for enveloping the package within the wrapper.

8. In a package-wrapping machine embracing means for printing labels on a web of paper, means for cutting the printed web into wrapper lengths or blanks each bearing a label, having its margins remote from the margins of the wrapper, means for gumming the unprinted surface of the label of the wrapper, means for depositing a package on said gummed surface, means for folding the longitudinal edges of the wrapper on the package and upon itself, and means for grasping and rotating the wrapper and package to infold the latter within the former.

9. A package-wrapping machine embracing means for printing grouped package and wrapper labels on a web of paper, means for cutting the web into wrapper lengths or blanks each bearing a package-label and a wrapper-label, means for gumming the unprinted surface of the package-label, means for placing a package on said gummed surface, means for folding the longitudinal ends of the blank upon the package and itself, and means for grasping and rotating the package and blank and wrapping the former in the latter.

10. A package-wrapping machine embodying in combination means for printing labels

on a web of paper, means for cutting the web into wrapper lengths or blanks, means for placing the package to be wrapped upon a wrapper, means for folding the longitudinal edges of the wrapper upon the package and itself and means for grasping and rotating the package and wrapper.

11. A wrapping - machine embodying in combination means for printing labels on a web of paper in pairs, means for cutting the web into wrapper lengths or blanks, each bearing a package-label and a wrapper-label, means for placing a package on the package-label of the wrapper, means for folding the longitudinal edges of the wrapper upon the package and itself, and means for subsequently grasping and rotating the wrapper and package.

12. A wrapping - machine embodying in combination means for printing labels on a web of paper, means for cutting the web into wrapper lengths or blanks, means for placing the package to be wrapped on the cut blanks, means for folding the longitudinal edges of the blank over on the package and itself, and means for subsequently grasping and rotating the said package and blank.

13. A wrapping - machine embodying in combination, means for printing labels on a web of paper, means for cutting the printed web into wrapper-blanks each bearing a label at a determined distance from its end, means timed to deposit a package upon one of said labels, and means for folding the longitudinal edges of the blank and wrapping the blank around said package.

14. In a wrapping-machine, in combination, means for printing labels on a web of paper, heating apparatus for immediately drying the freshly-printed labels, means for cutting the web into wrapper-blanks each bearing a label, means for folding the longitudinal edges of the blank upon the article and upon itself, means for grasping and rotating the article and blank, a main driving-shaft, and operative connections between said shaft and the printing, cutting and wrapping mechanisms.

15. In a wrapping-machine, the combination with printing mechanism to operate upon a traveling web of paper, means for cutting the printed web into wrapper-blanks, means for gumming the under surface of said printed portion and the rear of the blanks, means for placing the article to be wrapped upon the gummed surface of the printed portion, means for feeding cushioning-blanks onto the wrapper-blanks adjacent the article being wrapped and means for wrapping the two blanks about said article.

16. In a wrapping-machine the combination with printing mechanism operating upon a web or roll of paper, a knife to cut the web into wrapper-blanks, means for placing an article to be wrapped upon the printed severed blanks, rock-shafts journaled beneath the feeding-table and carrying fingers for folding the

longitudinal edges of the blanks, and means to grasp the article being wrapped and the blank and wrap the former within the latter.

17. In a wrapping-machine, the combination with rock-shafts carrying fingers for folding the longitudinal edges of a wrapper upon a package and upon itself, means for operating said rock-shafts and mechanism for grasping and rotating the wrapper and infolded package to completely inclose said package in said wrapper.

18. In a wrapping-machine, rock-shafts carrying fingers adapted to operate to fold the longitudinal edges of the wrapper, a wheel provided with a cam-groove and intermediate levers to operate said rock-shafts, in combination with means for rotating the article being wrapped and the wrapper simultaneously, to securely inclose the article within the wrapper.

19. In a wrapping-machine, the combination with printing mechanism to operate upon a traveling web of paper, means for cutting the printed web into wrapper-blanks, means for pasting the under surface of the printed portion and the rear ends of said blanks, means for placing an article to be wrapped upon the pasted printed portion of the blank, means for feeding cushion-wrappers onto the blanks adjacent the article being wrapped and means for wrapping the two blanks around said article.

20. In a wrapping-machine, the combination with printing mechanism to operate upon a web or roll of paper, a knife to cut the web into wrapper-blanks, means for placing an article to be wrapped upon the printed severed blanks, rock-shafts journaled beneath the feeding-table and carrying fingers for folding the longitudinal edges of the blanks, and means to grasp the article being wrapped and the blank and wrap the former within the latter.

21. In a wrapping-machine, in combination, mechanism for printing and drying grouped package and wrapper labels on a continuous web of paper, mechanism for cutting said web into wrapper-blanks and partially severing the package-labels therefrom, means for gumming the back of said package-label and the rear edge of the blank, means for placing a package on the gummed surface of the package-label, and means for folding and wrapping said blank around the package.

22. In a wrapping-machine, the combination of mechanism for printing labels upon a web of paper, and drying the same, mechanisms for cutting the web into wrapper-blanks, perforating and pasting said blanks, and mechanism for folding the blank upon the article being wrapped and wrapping it around the same, said mechanisms all being actuated from the main shaft of the machine.

23. In a wrapping-machine, the combination with the support or table on which the blanks are fed and folding-fingers carried

thereby, of means for placing the article to be wrapped on the wrapper, wrapping mechanism and means imparting to said wrapping mechanism longitudinal movement with respect to the support.

24. In a wrapping-machine, the combination with the support or table on which the blanks are fed and folding-fingers carried thereby, of means for placing the article to be wrapped on the wrapper, wrapping mechanism and means imparting to said wrapping mechanism vertical and longitudinal movement with respect to the support.

25. In a wrapping-machine, the combination with the support or table on which the blanks are fed, and folding-fingers carried thereby, of means for placing the article to be wrapped on the wrapper, wrapping mechanism and means imparting intermittently to said wrapping mechanism vertical and longitudinal movement with respect to the support or table.

26. In a wrapping-machine, the combination with the support on which the blanks are fed, of means for pasting the edge of the blanks, means for depositing the article to be wrapped on the blanks, folding-fingers carried by the support, and devices to grasp and rotate the assembled article and wrapper to wrap the latter around the former.

27. In a wrapping-machine, the combination with the support on which the blanks are fed, of means for pasting the edge of the blanks, means for depositing the article to be wrapped on the blanks, means for depositing a cushion-wrapper on the blank adjacent said article, folding-fingers carried by the support, and devices to grasp and rotate the assembled article and wrappers to wrap the folded blank and cushion-wrapper around the article.

28. In a wrapping-machine, the combination with the supporting-frame and table of a vertically-movable hopper to deposit articles singly upon a wrapper-blank on the table, folding devices associated with the table, wrapping devices normally positioned to rear of the hopper, and a support for the wrapping devices movable longitudinally to bring said wrapping devices beneath the hopper.

29. In a wrapping-machine the combination with the supporting-frame and table of a shaft carried by the frame and provided with gears having cam-grooves, a hopper having means to deposit articles on the table, wrapping mechanism normally positioned to rear of the hopper, a longitudinally-movable frame supporting the wrapping mechanism, and connections between the movable frame, the wrapping mechanism and the cam-grooves of the gears to advance said movable frame toward the hopper and move the wrapping mechanism to grasp an article.

30. In a wrapping-machine, the combination with the supporting-frame and table, of a shaft carried by the frame and provided with

gear-wheels having cam-grooves, a gear-ring operable intermittently by one of the gear-wheels, a hopper, wrapping mechanism normally positioned to rear of the hopper, a vertically and longitudinally movable frame supporting the wrapping mechanisms, friction-wheels provided with cam-grooves connections between the movable frame, the wrapping mechanism and the cam-grooves of the friction-wheels to advance the movable frame and wrapping mechanism toward the hopper, and operable connections between said frame and the gear-ring to give vertical reciprocation to said frame and the wrapping mechanism.

31. In a wrapping-machine, the combination with the supporting-frame and table, of a shaft carried by the frame and provided with gear-wheels having cam-grooves, a gear-ring operable intermittently by one of the gear-wheels, a hopper, rotatable wrapping mechanism normally positioned to rear of the hopper, a longitudinally-movable frame supporting the revolute wrapping devices, a shaft driven intermittently from the gear-ring, and extensible driving connections between said shaft and the rotatable wrapping devices.

32. In a wrapping-machine, the combination with the supporting-frame and table, of a shaft carried by the frame and provided with gear-wheels having cam-grooves, a gear-ring operable intermittently by one of the gear-wheels, a hopper, a longitudinally-movable frame supporting the revolute wrapping devices, eccentrics for raising and lowering said frame, a shaft driven intermittently from the gear-ring, and extensible driving connections between said shaft and the rotatable wrapping devices.

33. In a wrapping-machine, in combination, means for feeding a web of paper, printing and drying mechanism, means for severing the printed web into wrapper-blanks, pasting mechanism; and means for surrounding the printed portion with a weakened break-line, comprising a shaft suitably connected with the main shaft of the machine, an eccentric on said shaft, a strap encircling said eccentric, and a platen connected to the strap and provided with pins or punches.

34. In a wrapping-machine, in combination, means for feeding a web of paper, printing and drying mechanisms, means for severing the printed web into wrapper-blanks, a device for surrounding the printed portion with a weakened break-line, and a pasting device comprising a block having separated surfaces to distribute paste within the weakened line of the printed portion and the rear edge of the wrapper-blank, said block being carried on a shaft driven from the main shaft of the machine.

35. In a wrapping-machine, in combination, means for printing and drying a web of paper, means for severing the web into wrapper-blanks, means for perforating the outline of

the printed portion and pasting the under surface thereof and the rear edge of the wrapper-blank, a hopper for cushion-wrappers having a slotted guideway in its bottom, a feeding-head reciprocating in said guideway and having a feeding-finger projecting through the slot of the hopper bottom, and operative connections between said head and the main shaft of the machine.

36. In a wrapping-machine, in combination, means for feeding a web of paper, printing and drying mechanism, means for severing the printed web into wrapper-blanks, means for surrounding the printed portion with a weakened line, means for pasting said printed portion and the rear edges of the blanks, and article-feeding mechanism actuated from the main shaft of the machine, comprising a vertically-movable open-ended hopper, retaining-fingers at the lower end thereof to normally support a tier of articles in the hopper, and stops to move the fingers from beneath the lower article near the limit of the downward movement of the hopper.

37. In a wrapping-machine, in combination, means for printing and drying a web of paper, means for severing the web into wrapper-blanks, means for perforating the outline of the printed portion and pasting the under surface thereof and rear margin of the blank; means to deposit an article on the pasted surface of the printed portion, means to fold the longitudinal edges of the wrapper upon the article, means for grasping the article and wrapper and means for rotating the grasping means to envelop the article in the wrapper.

38. In a wrapping-machine, in combination, means for printing, drying, cutting, perforating and pasting a wrapper-blank, means to deposit an article to be wrapped on the back of the printed portion clasps for grasping the article being wrapped, and means to move said clasps longitudinally and laterally of the machine to grasp the article and rotate the clasps after engagement with said article, substantially as described.

39. In a wrapping-machine, in combination, means for printing, drying, perforating and pasting a wrapper-blank, means to deposit the article to be wrapped on the under surface of the printed portion clasps for grasping the article being wrapped, and means to move said clasps to engage the article and wrapper-blank and to rotate the same on a vertically-shifting axis, substantially as set forth.

40. In a wrapping-machine, in combination, means for depositing the article to be wrapped upon a wrapper-blank, means to engage the article and wrapper-blank and rotate the same on a vertically-shifting axis.

41. In a wrapping-machine, in combination, means for depositing the article to be wrapped upon a wrapper-blank, means to engage the article and wrapper-blank and rotate the same on a vertically-reciprocating axis.

42. In a wrapping-machine, in combination, means for depositing the article to be wrapped on a wrapper-blank, clasps for grasping the article being wrapped, and means to move said clasps longitudinally and laterally of the machine to grasp the article and rotate the clasps after engagement with said article, substantially as described.

43. In a wrapping-machine, in combination, means for printing, drying, cutting, perforating and pasting a wrapper-blank, means to deposit the article being wrapped on the under surface of the printed portion clasps for grasping the article being wrapped, means to move said clasps longitudinally and laterally of the machine to grasp the article and rotate the same on a vertically-shifting axis, substantially as set forth.

44. In a wrapping-machine, the combina-

tion of the supporting-frame and table, a counter-shaft mounted thereon and provided with wheels having cam-grooves, a gear-ring receiving intermittent motion from one of said wheels, a hopper operatively connected with a cam-groove to deposit an article periodically on the table, and clasps located normally in rear of the hopper, and operative connections between the gear-ring and clasps to move the latter to grasp and rotate the article, substantially as described.

In testimony whereof I have signed my name to this specification in the presence of two subscribing witnesses.
